UNITED STATES PATENT OFFICE.

BENJAMIN FRANKLIN WOODING, OF DENVER, COLORADO.

RAILWAY SIGNALING APPARATUS.

1,091,102.

Specification of Letters Patent. Patented Mar. 24, 1914.

Application filed May 23, 1911. Serial No. 328,989.

To all whom it may concern:

Be it known that I, BENJAMIN F. WOODING, a citizen of the United States, residing in the city and county of Denver and State of Colorado, have invented certain new and useful Improvements in Railway Signaling Apparatus; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to improvements in railway signaling apparatus.

In my improved construction the track is blocked.

20 My special object is to automatically give an alarm and simultaneously apply the air brakes whenever the train comes into dangerous proximity with another train. I employ a magnet, which is mounted upon the train and normally in a closed circuit, the 25 circuit being carried wholly by the train; and part of the train, as the locomotive, is equipped with two oscillatory hangers through which the normally closed train circuit is completed. At suitable intervals 30 along the track contacts are arranged, adapted to engage one of these hangers, whereby the train circuit through the magnet is broken, and a circuit immediately re-established through the track and relays 35 arranged along the track, in case the track is clear. However, if a train has entered a block in dangerous proximity to another train, the relay circuit will be short-circuited through the track, whereby the relay magnet 40 is deenergized, permitting its armature to fall away from the contacts, whereby the circuit of the approaching-train magnet is broken, in which event, the armature of the magnet moves downwardly and opens a 45 valve which releases the air of the air brake system, applies the brakes, and operates a whistle, thus simultaneously stopping the train and giving the alarm. In the event that the track is clear, the energized condition of the train magnet is not only maintained, but a signal bell upon the train is 50 sounded while the train hanger is in engagement with a track contact. These track contacts are arranged at such intervals as to 55 fully protect the trains and prevent their approaching each other in such proximity.

as to result in collision. Each train is equipped with a hanger on each side thereof. The track contacts are arranged upon one side of the track only, hence the hanger 60 upon one side of the train engages these contacts when the train is moving in one direction and the hangers on the opposite side of the train when the train is traveling in the opposite direction.

65 Having briefly outlined my improved construction, I will proceed to describe the same in detail, reference being made to the accompanying drawing in which is illustrated an embodiment thereof.

70 In this drawing: Figure 1 is a section taken through the cab of the locomotive, illustrating my improved signaling mechanism. Fig. 2 is a longitudinal section taken through one of the oscillatory hangers of the train, 75 the same being shown on a larger scale. Fig. 3 is an elevation of one of these hangers viewed in the same position as shown in Fig. 2. Fig. 4 is a side view or a view looking at right angles to Figs. 2 and 3. Fig. 5 80 is a diagrammatic view illustrating the track relays and the circuits in which they are located.

85 The same reference characters indicate the same parts in all the views.

Let the numeral 5 designate one of the track rails and 6 the opposite rail. As illustrated in the drawing, the track rail 5 is continuous or forms an uninterrupted electrical conductor, while the continuity of the track rail 6, so far as its electrical conductivity is concerned, is interrupted at suitable intervals, as shown at 7, thus forming the track into blocks. The distance between two of the interruptions 7 may be termed 90 a block for the purpose of explaining my signaling system.

95 The train equipment will now be explained.

Suitably mounted upon the train is a magnet 8, having a vertically disposed movable armature 9, with which is connected a rod 10, whose lower extremity is provided with a valve 12 which normally closes a port 13 in communication with the air of the air 100 brake system. Under normal conditions, or when the coils 14 of the magnet are energized, the armature of the magnet is supported in such a position as to close the valve 12. When, however, the circuit is 105 broken through the coils 14, the armature falls and opens the said valve, releasing the 110

air sufficiently to apply the brakes and at the same time sound a whistle 15 with which the air communicates by way of a pipe 16. Upon a framework 17, supporting the magnet, is journaled a rock shaft 18, with which is connected a lever arm 19. Upon this rock shaft is also mounted and made fast, a lifting device 20 which is bifurcated to receive the stem 10 of the armature. After 5 the magnet has been deenergized and its armature drops to open the air valve 12, the lifter 20 is employed for bringing the armature of the magnet within acting distance, when the circuit is again closed through the 10 magnet coils, this lifting operation being accomplished by taking hold of the lever 19 and moving the same upwardly, whereby a lifting movement is imparted to the device 20, upon which the armature rests when the 15 circuit is broken. The coils of the magnet 8 are located in two circuits one of which is carried wholly by the train, while the other is completed through the track rails and relays arranged along the track, as heretofore 20 intimated. These circuits will now be explained.

The normal train circuit is provided with a source of electricity 21 from the positive pole 22 of which an electrical conductor 23 25 leads to a lamp 24, whence a conductor 25 leads to a contact 26 mounted on a stationary part of the train, the said contact being insulated from the metal part of the train and arranged to coöperate with a contact 27 30 carried by and insulated from a metal hanger 28, pivoted on the train as shown at 29, whereby it is permitted an oscillatory movement. The contact 27 is normally held in engagement with the contact 26 by a 35 spiral spring 30 located in a recess 31, surrounded by insulating material 32. The upper curved surface of the hanger 28 is covered with a layer of insulating material, as shown at 33. In the bottom of the recess 40 31 is located a metal part 34 from which leads a conductor 35, which is insulated from the body or metal part 36 of the oscillatory hanger. The lower extremity of the conductor 35 is exposed and directly connected 45 with a metal part 37 of the hanger, this part being arranged to engage contacts 38 arranged along the track at suitable distances 50 to compel every train so equipped to automatically test the track in either direction 55 for the purpose of determining whether or not other trains are in dangerous proximity.

Each hanger 29 is provided with a laterally projecting arm 39 carrying a roller 40 occupying a position between two leaf 45 springs 41 and 42, the springs being under such tension as to maintain a rigid normal position.

The electric current, if we assume that the hanger 28 is in its normal or vertical position will pass through the conductor 35, and

at the lower extremity of the said conductor, the current will escape into the metal part of the hanger 28, and pass thence upwardly to the pivot 29 and the frame supporting said arm to a terminal 4 insulated from the car body, and thence through a conductor 43 of one terminal 45 of the magnet coils 14, and thence through another terminal 46 of the said coils to a conductor 47, to a contact 48 insulated from the metal body of the car, 70 but connected with the bracket frame 49, also insulated from the metal car body, the circuit being completed through the frame supporting the oscillatory hanger, thence from the lower extremity of said hanger 75 through the conductor 35 to the contact 27, thence through its coöperating contact 26, and a conductor 51 to the opposite pole 52 of the electrical source 21, completing the 80 circuit. I have thus traced the path of the 85 circuit through the coils 14 of the magnet under normal conditions, and when neither oscillatory hanger is moved out of its vertical position by engaging a track contact 38.

Referring now to Fig. 5, I will assume that 90 the train, conventionally illustrated in Fig. 1, is in the full line position in Fig. 5, the said train being designated by the numeral 53. I will also designate the various blocks illustrated in Fig. 5, as A, B, C, D, and E. 95 According to this arrangement, the train 53 is in block C, and if we assume that the track is clear as to block D, the circuit may be described as follows: Whenever an oscillatory hanger 28 engages a contact 38, the said hanger is thrown to the position indicated 100 at the left in Fig. 1, whereby the two contacts 26 and 27 are thrown out of engagement and the circuit broken through the coils 14 of the magnet 8, through the battery 21. However, as soon as the circuit is broken through the last named battery, the 105 circuit is closed through the coils 14 of the magnet 8, through a second battery 55, also carried by the train, in the following manner: From the pole 56 of the battery 55, a conductor 57 leads to a terminal 58 of the coils 14 of the magnet 8, thence from an opposite terminal 46 of the said coils, through 110 a conductor 47, a contact 48 and the metal bracket 49, the metal part 36 of the oscillatory hanger 28 on the lefthand side (see Fig. 1), thence through one member 59 of the track contact 38, thence through a conductor 60 to a stationary contact 65, thence through 115 a coöperating contact 66 mounted on an arm 67, normally acted on by a magnet 86 to maintain a closed circuit through the relay, thence through the arm 67 of the relay, through a short conductor 68 of the relay, to the track rail 5, thence through the said rail to a wheel 69 of the train, thence through the metal part 44 of the car to a point 70 thereon, thence through a conductor 71 to a bell 72, thence from the bell through a con- 120

ductor 73 to the negative pole 74 of the battery, completing the circuit. Now, instead of the track being clear, as I have assumed in the description immediately preceding, in other words, if there is a train 54 in block D, the metal wheels and axle of this train will short-circuit the current between a section 75 of the track rail 6 and the track rail 5, whereby the current is cut off from the magnet 86 and the latter deënergized. As soon as this occurs, the armature 67 will fall to the dotted line position in Fig. 5, thus breaking the circuit heretofore traced through the armature 67 of the relay at the extreme left of Fig. 5, and the coils 14 of the magnet 8. As soon as this occurs, the armature 9 of the last named magnet will drop downwardly opening the valve 12 and allowing the air to escape through the port 13, sufficiently to release the air of the air brake system and apply the automatic brakes simultaneously with the sounding of the whistle 15.

The circuit of the magnet 86 in block D, may be traced as follows: From the positive pole 76 of a battery 77, a conductor 78 leads to a section 75 of the track rail 6, thence from the said track rail section through a conductor 79 to a terminal 80 of the relay magnet 86, thence from the opposite terminal 81 through a conductor 82 and the armature 67 at a point 83, thence through the conductor 68 to the track rail 5, thence from the said rail through a conductor 87 to the negative pole 84 of the battery 77, completing the circuit. Now, it is evident that, as soon as a train, as that designated 54, has entered a block D, the magnet 86 will be deënergized by the short-circuiting of the current through the train 54, as heretofore explained.

From the foregoing description, it will be understood that, if a train 53 enters block C, and a train 54 is in the adjacent block D, train 53 will be warned as soon as its oscillatory hanger 28 engages the member 59 of a contact 38, since, in this event, the circuit will be interrupted through the coils 14 of the magnet 8 of the train 53 by breaking the circuit through the relay in block D, and allowing the armature to fall, whereby the air valve is opened and the air released for brake-setting purposes on train 53, a whistle on the same train being simultaneously sounded, as heretofore explained.

Attention is called to the fact that while the current which supplies the magnets 86 is short-circuited through the track rails 5 and 6 when a train enters a block, thus de-

energizing the corresponding magnet 86 and breaking the circuit through the magnet 8 on the train, the same result will follow the breaking of a rail section 75 for the breaking of the rail 5 within the limits of any block. Hence, if a rail is broken, the air brakes will be applied and a whistle sounded on a train in an adjacent block in the same manner as if a train had entered a block, as heretofore described.

Attention is called to the fact that the contacts 59 and 90 are so arranged upon one side of the track that when the train is going toward the left (Fig. 5), one of the hangers attached to the train will engage the inner faces of the contacts 59 at their right hand extremities, while when the train is traveling toward the right (also Fig. 5), the hanger upon the opposite side of the said train will engage the outer faces of the contacts 90 at their left hand extremities. This is true because the left hand extremity of the outer face of each contact member 38 is practically in alinement with the right hand extremity of the inner face of said member, although the first named extremity is a trifle closer; *i. e.*, a distance equal to the thickness of one of the contact members, to the track 6, than the last named extremity.

Having thus described my invention, what I claim is:

1. In combination with an engine cab, a contact brush comprising a lever pivoted upon said cab to swing vertically transversely of the cab, said lever being constructed of conducting material and a conductor extending through said lever from end to end and insulated therefrom except at its lower extremity.

2. In combination with an engine cab, a bracket mounted upon said cab, a lever mounted intermediate its ends upon a horizontal pivot in said bracket, an arm extending outwardly at an angle from said lever, a double spring device secured upon and insulated from the cab, said spring device being adapted to bear against the opposite sides of said arm, tending to hold the latter in a predetermined position and to return it to said position when moved therefrom and an electric conductor extending through said lever from end to end and insulated therefrom except at the lower extremity.

In testimony whereof I affix my signature in presence of two witnesses.

BENJAMIN FRANKLIN WOODING.

Witnesses:

F. E. BOWEN,
C. E. RADEN.
